UNITED STATES PATENT OFFICE.

ERNEST STUART DANIELS, OF WASHINGTON, DISTRICT OF COLUMBIA.

SHIPPING BOX OR CASE STRUCTURE.

Application filed November 12, 1924. Serial No. 749,543.

To all whom it may concern:

Be it known that I, ERNEST STUART DANIELS, a subject of the King of England, residing at Washington, in the District of Columbia, have invented certain new and useful Improvements in Shipping Box or Case Structures; and I do hereby declare the following to be a full, clear, and exact description of the invention, such as will enable others skilled in the art to which it appertains to make and use the same.

This invention relates to shipping cases or crates, and more particularly to packing boxes or containers for food stuffs and general merchandise, in respect to which a strong, durable and non-collapsible container of comparatively light weight may be desired or required adequately to protect the goods or merchandise from injury incident to careless or rough handling during shipment, and is a further development of the idea disclosed in my Patent No. 1,472,635, granted October 30, 1923.

It has heretofore been necessary, especially with light boxes, crates or containers constructed from very thin planking or boards, to bind the ends or sides of the same with encircling metal strips or stout wire, or to apply reinforcing brads thereto in order to hold the ends or sides of assembled sections together and prevent splintered pieces or portions of the wood from falling out of place, allowing the boxes to collapse should the wood crack or split as a result of the strain from rough handling.

The principal object of the present invention is to provide an improved light weight box or packing case structure in which top, bottom, ends or side pieces or sections of very thin material are reinforced in such manner as to positively hold the same together and prevent them from collapsing or breaking apart, even though such pieces or sections may crack or split from top to bottom or from end to end.

Simplicity of design, inexpensive of manufacture, strength and maximum durability in use, are further desiderata which have been borne in mind in the production of my improved packing box or crate structure.

The invention will first be hereinafter more particularly described with reference to the accompanying drawings which are to be taken as a part of this specification and then pointed out in the claim at the end of the description.

In said drawings, Fig. 1 is a perspective view of a box constructed in accordance with my invention, the top being shown in elevated position above the box;

Fig. 2 is a perspective view of a box or crate top, bottom, end or side section or panel embodying a feature of my invention;

Fig. 3 is a fragmentary perspective view of the preferred form of reinforcing strip or spline by which several pieces of thin material are compositely held together; and

Fig. 4 is a perspective view of a modified form of reinforcing strip.

Referring to the drawings in which like reference numerals are used to designate the corresponding parts throughout the several views, 5 denotes a box section which may be formed either from a single piece of thin board or in two or more pieces or strips of very thin planking or board of the same or different widths and of equal length joined together as illustrated in Fig. 2, to provide composite sections or panels for the top, bottom, end or sides of the box, the dimensions of the respective sections or panels depending upon the dimensions desired for the completed box.

A complete box such as shown in Fig. 1 may thus be constructed from composite sections or panels formed individually as above stated to form the bottom 6, the ends 7, sides 8 and top 9, respectively.

The sawed off or transverse ends of the pieces arranged together to form these composite sections or panels, are reinforcingly splined and rigidly held together by a transversely corrugated metallic strip or shook 10, which is pressed into the aligned edges of the pieces at opposite ends of the sections, thus flexibly binding the several pieces together as a unitary structure, rendering them inseparable and providing a retaining means preventing them from coming apart should any one or all of the several pieces of the composite panels split from end to end. Thus a metallic corrugated shook or spline is provided in the transverse end edges or margins of the several pieces of the composite sections or panels at substantially right angles to the grain of the wood in the respective pieces thereof.

If desired, the metallic strips or shooks 10 may be coated with a glue to assure a tight union between the parts and prevent the same from jarring loose after long continued

use or swelling of the wood resulting from exposure to the weather.

Flattened extremities of said shooks or splines are preferably extended transversely beyond the edges or margins of the respective sections as shown in Fig. 1, to provide fastening clamps or flap portions 10^a, by which the assembled sections may be more securely bound together to form a strong and rigid box structure.

Referring to the modification shown in Fig. 4, metallic strips 11 of a slightly different form, may if preferred be employed, said strips being flat substantially throughout their length and formed with a series of transverse corrugations only at their respective extremities, the latter strips being applied under pressure to the end edges or margins of the composite sections or panels 5 as shown in Fig. 2, in the same manner as that described with reference to the splines or strips 10.

From the foregoing it will be readily understood that I have provided a novel and valuable improvement in box or crate structure. By the means described, a strong durable and non-collapsible box or crate of very light weight may be constructed from thin pieces of wood or other fibrous material 30 having a natural tendency to crack or split under slight strain, the invention being especially applicable to lighter weight boxes constructed with material of one-fourth inch thickness, although it is readily adaptable to 35 containers constructed from thinner or thicker material as well. It is a well known fact that boxes and crates as heretofore constructed with very thin pieces of wood, are exceedingly fragile and quickly break apart 40 or completely collapse in use, as the thin wood easily cracks or splits when any appreciable torque or strains are imposed thereon under shipment, so that they are rendered practically useless in a short time 45 and are wastefully thrown aside for fire wood. A light but strong box constructed of very thin pieces of lumber for purposes of economy in cost of production and in freight charges, has long been a commercial

need, and it is believed the present invention 50 fully supplies that need, providing a box or container of the desired minimum weight, which will nevertheless meet all reasonable requirements of strength and durability so as to adequately protect goods 55 and merchandise under shipment. My improved compositely formed box sections or panels with novel reinforcement means against breakage or collapse upon splitting or cracking of the wood, will permit an 60 appreciable saving in lumber, which is an economic consideration of universal importance. The advantages and desirability of a packing box, case, crate or other container constructed with non-collapsible sections or 65 panels, respectively forming the top, bottom, ends and sides of the same will be obvious, and the novelty and value of the invention will be fully appreciated, since the labor and expense heretofore necessary 70 in binding lighter weight cases or crates with embracing metal bands or wire to hold the same together, may be wholly eliminated. Needless destruction in opening or unpacking containers upon arrival at destination may also be avoided by the use of 75 boxes, crates and the like, constructed in accordance with my invention, since there are no binding bands or wire to be removed 80 from place before the lid can be raised.

Having thus described my invention, what I claim as new and desire to secure by Letters Patent of the United States is:—

A wooden section forming the top, bottom, end or side of a packing box or case, 85 comprising a plurality of joined panels of equal length, said panels being compositely united by a corrugated metallic strip pressed into the transverse edges thereof at opposite ends of the section, said strips running at 90 substantially right angles to the grain in each of the panels and extending throughout the width of the section with their respective ends projecting slightly beyond the margins of said section to provide fastening 95 clamps or flaps therefor.

In testimony whereof I affix my signature.
ERNEST STUART DANIELS.
